UNITED STATES PATENT OFFICE

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY

BUTTONHOLE SEWING MACHINE

Application filed May 31, 1929. Serial No. 367,512.

This invention relates to sewing machines of the buttonhole cutting and stitching type and has for an object to improve the construction and timing of the work-clamp lifting mechanism of my copending application, Ser. No. 258,772, filed Mar. 3, 1928, so that it will function not only to relatively separate the under surface of the work and the thread for the action of the thread-cutter, but also to 10 relatively separate the work-clamp and needle-throat member vertically to remove the needle-throat member from the stitching aperture in the lower work-clamp plates preparatory to the buttonhole-cutting operation; 15 such provision avoiding the necessity of cutting a needle-throat clearance slot in the clamp-plates leading from the stitching aperture, and permitting the work to be clamped entirely around the stitching aperture, as 20 disclosed in the Allen Patent No. 1,360,704, of Nov. 30, 1920.

Stated more generally, the invention has for an object to provide an organized button-hole cutting and sewing machine having 25 thread-cutting mechanism below the work, with means accomplishing the double result of insuring the proper action of the thread-cutting mechanism and permitting the work to be clamped entirely around the stitching 30 aperture in the work-clamp.

To the attainment of the ends in view, there is provided means for relatively separating the needle-throat member and work-clamp vertically at the completion of the sewing 35 operation and holding them so separated for the action of both the buttonhole-cutting and thread-cutting mechanisms. This is preferably accomplished by providing a cam running with the usual feed-cam and operating 40 through suitable connections to lift the work-clamp prior to the rapid feed of the work-clamp from stitching to buttonhole-cutting position; such cam and connections holding the work-clamp lifted in buttonhole-cutting 45 position for the action of the buttonhole-cutting and thread-cutting mechanisms, and until the work-clamp is shifted forwardly into stitching position during the succeeding buttonhole-producing cycle.

50 Referring to the accompanying drawings,

Fig. 1 is a side elevation of a buttonhole cutting and stitching machine embodying the invention. Fig. 2 is a horizontal section through the standard of the machine, showing the bed in plan. Fig. 3 is a bottom plan view of the machine. Fig. 4 is a front end elevation. Fig. 5 is a side-elevation of the work-clamp lifting mechanism. Fig. 6 is a section on the line 6—6, Fig. 5. Fig. 7 is a section on the line 7—7, Fig. 6, and Figs. 8, 9, 10 and 11 are perspective views of elements of the work-clamp lifting mechanism.

The term "buttonhole" as used herein and as generally understood in this art, applies broadly to the product of a machine of the buttonhole making type and, of course, includes circularly stitched holes or eyelets. The machine herein shown and described, and in which the invention is embodied in its preferred form, is adapted to cut and stitch circular eyelets, the stitch being preferably formed from one needle-thread and two looper-threads concatenated in accordance with the disclosure of the Allen Patent No. 1,537,022, of May 5, 1925.

The machine illustrated is of the type disclosed in the patent to Allen, No. 15,324, re-issued April 4, 1922, and comprises the bed 1, standard 2 and overhanging bracket-arm 3 terminating in the head 4. The stitch-forming mechanism is constructed substantially in accordance with the disclosure of the Allen et al. Patent No. 1,372,473, of Mar. 22, 1921, and comprises the reciprocating and laterally jogging needle 5 and the usual under-thread mechanism mounted on the rotary turret 6 and including two threaded loopers 7, 8 and cooperating loop-detainers 9, 10; the threaded looper 8 being substituted for the non-threaded looper of the Allen et al. Patent No. 1,372,473, in accordance with the disclosure of the Allen Patent No. 1,560,635, of Nov. 10, 1925. The turret 6 also carries the usual needle-throat member 11. The period of operation of the stitch-forming mechanism is controlled by the usual stop-motion device 12 by which the flow of power from the continuously running belt-pulley 13 to the sewing shaft 14 is established and interrupted.

The buttonhole-cutting mechanism is con-

structed substantially in accordance with the disclosure of said Allen reissued patent and comprises the upper and lower cutter-levers 15, 16 which are fulcrumed at 17 on the travel-
5 fulcrum-block 18 which carries the cutter-levers forwardly from the retracted position, shown in full lines in Fig. 5, to button-hole cutting position, shown in dotted lines in such figure. The cutter-levers and ful-
10 crum-block derive their operative movements from the usual cutter-advancing and -retracting cam 19 and cutter-closing cams 20, 21 on the cutter-shaft 22 which is actuated through the usual clutch-connection from a constantly
15 running belt-pulley 23.

The work-clamp, except as hereinafter noted, is of the usual construction disclosed in said reissued patent. It comprises the lower work-supporting plates 24 and upper
20 clamping feet 25 carried by the clamp-arms 26 fulcrumed at 27 on the blocks 28 mounted on the plates 24. The clamp-plates 24 are carried by the usual cross-slide plate 29 which, in turn, is carried by the usual longitudinal
25 slide-frame 30. The longitudinal slide-frame receives its motion from the usual link-con-
nection 31 with the lever 32 fulcrumed at 33 on the bed 1 and having a follower 34 entering the longitudinal feed cam-groove 35 in
30 the feed-wheel 36. The cross-slide plate is actuated by the lever 37 fulcrumed at 38 on the bed 1 and having a follower 39 entering the lateral feed cam-groove 40 in the cam-
35 disk 41 fixed to the cross-shaft 42 which is connected to run with the feed-wheel 36 by the one-to-one bevel gears 43. The feed-wheel 36 and connected cross-shaft 42 and cam-disk 41 are given a step-by-step feeding movement through the usual connections with the sew-
40 ing shaft 14, to place the stitches around the buttonhole. They are also given a rapid continuous movement, both prior and subsequent to sewing, by the continuously running rapid-feed shaft 44 which operates these parts
45 at the proper times through the worm-gear-
ing 45 and the usual clutch-connection 46. During the rapid continuous movement of the feed-cams, the work-clamp is shifted forwardly from buttonhole-cutting position,
50 Fig. 5, to sewing position, in which the sewing aperture 47 in the work-clamp is in register with the needle-throat member 11. When the sewing is completed the work-clamp is rapidly returned to its initial or buttonhole-cut-
55 ting position, during which movement the under threads and a loop of the upper thread around one of the loopers are drawn out from the needle-throat member and extend along the under side of the work to the last stitch.

The work-clamp is closed by a rocking movement of the connected rock-shaft sections 48 one of which has fixed thereto the rearwardly extending arm 49 which is de-
60 pressed by the automatically operated clamp-
65

closing lever 50. The rock-shaft sections 48 may be manually operated to close the work-
70 clamp by rearward motion of the usual up-
wardly extending finger-piece 51 fixed to the same rock-shaft section 48 which carries the rearwardly extending arm 49.

The thread-cutter is constructed substantially in accordance with the disclosure of the patent to Allen No. 1,579,200, of April 6, 1926, and of my said copending application, Ser. No. 258,772. It comprises a scissors device having an upper pointed blade 52 fixed to and carried by the thread-cutter lever 53 which is fulcrumed at 54 on the machine frame. Pivoted at 55 to the upper scissors-
80 blade 52 is the lower scissors-blade 56 the tail of which has a follower 57 entering the scissors-closing cam-slot 58 in the stationary cam-plate 59. This scissors device operates in a curved path in a vertical plane intersect-
85 ing the lead of the threads from the needle-
throat member 11 to the stitched buttonhole when the latter has been shifted to button-
hole-cutting position, Figs. 2 and 5.

The thread-cutter lever 53 is operated by a link-connection 60 with a lever 61 fulcrumed at 62 on the frame-bracket 63 and having a follower 64 entering the thread-cutter cam-
90 groove 65 in the vertical gear 43, as disclosed in the patent to Allen No. 1,600,206, of Sept. 21, 1926.

In the machine disclosed in my copending application, Ser. No. 258,772, means connected to be operated by the thread-cutting mechanism are provided for lifting by upwardly tilting the front end of the work-clamp during the advance of the thread-cutter to operative position; such lifting of the work-clamp effecting the separation from the under surface of the work of the threads to be cut and providing a space for entry of the point of the upper scissors-blade. According to this prior construction the work-clamp is immediately lowered to normal position during the retraction of the thread-cutter, in which lowered or normal position it is rapidly shifted into and out of stitching position.

According to the present improvement the work-clamp lifting mechanism is actuated by a cam on the cross-shaft 42 running with the feed-cams. The cam is so cut as to effect the lifting of the work-clamp at the completion of the sewing operation and prior to the rapid-feed of the work-clamp to buttonhole-cutting position. The work-clamp is held lifted during the thread-cutting and button-hole-cutting operations and during the rapid-feed of the work-clamp from buttonhole-cutting to sewing position, when it is lowered to its normal sewing level. By so lifting the work-clamp the double function is effected of relatively moving the needle-throat member and work-clamp vertically to permit of the horizontal shift of the work-clamp between sewing and buttonhole-cutting posi-
100

tions without the necessity of providing a needle-throat clearance slot in the lower work-clamping plates, and of relatively separating the sewing threads and the under

5 surface of the work to provide a space for the entry of the thread-cutter blade. The avoidance of the necessity of cutting a needle-throat clearance slot in the lower work-clamping plates permits the clamping-plates 10 to support and clamp the work entirely around the sewing aperture and avoids distortion of the work, as explained in the Allen Patent No. 1,360,704, previously referred to.

The lower clamp-plates 24 have at their 15 rearward ends the usual laterally slidable connection 66 with the undercut forward edge of the retainer plate 67 as disclosed in said Allen reissued patent. This connection is free enough to permit of the upward tilting of the work-clamp sections about such connection as a center. Connected to sockets in the front ends of the work-clamp sections are the ball-shaped upper ends 68 of pins 69 which are received in the tubes 20 25 fixed to the plate 71. The pins 69 are grooved at 72 for reception of the circular portions 73 of the latch-lever 74 which is fulcrumed at

75 on the plate 71. The latch-lever 74 is formed with recesses 76 which, when shifted 30 into register with the pins 69, permit upward removal of such pins from the tubes 70 in removing the clamp-sections from the machine. The spring 77 is adapted to bear upon the angularly related flats 78, 79 on the 35 latch-lever 74 to retain the latter in its two positions.

The tubes 70 are slidably received in the 40 apertures 80 in the block 81 secured to the cross-slide plate 29. The spring 82 yieldingly retains the clamp-plates 24 upon the cross-slide plate 29 and the stop 82' limits the downward movement of the plate 71 under the influence of the spring 82 when the pins 69 are released.

45 Disposed in underlapping lifting engagement with the plate 71 is the round nosed forward end of an arm 83 fixed to the rock-shaft 84 journaled in the bearing-bracket 85 mounted on the block 81. Fixed to the shaft 84 is a rearwardly extending arm 86 having a laterally extending pin carrying a roller 87 over which extends the forward end of a lever 88 fulcrumed on the pin 62 and having at its rearward end a follower 89 entering the cam-groove 90 in the cam-disk 91 fixed to the cross-shaft 42 which runs with the feed-cams 35 and 40. The lower edge 92 of the forward end of the lever 88 is disposed horizontally when the high portion 90' of the cam-slot 90 has rocked the lever 88 to lift the clamp-plates, as shown in Fig. 5. Hence, during the rapid feed of the work-clamp between sewing and buttonhole-cutting positions, the travel of the roller 87 longitudinally of the lever 88 imparts no rocking impulse

to the shaft 84 and no lifting or lowering movement to the work-clamp.

The cycle of operations is as follows:—

Starting with the machine at rest, as shown in Fig. 1, with the work-clamp in buttonhole-cutting position where it is held lifted by the high part 90' of the cam-groove 90, a work-piece is presented beneath the raised clamp-feet 25 and the machine is started, whereupon the clamp-feet 25 are automatically closed upon the work and the work-clamp rapidly moved forwardly from its initial position to stitching position. When the work-clamp arrives in stitching position, the eccentric part 93 of the cam 90 engages the follower roll 89 and rocks the lever 88 in a direction to raise its forward end, thereby lowering the work-clamp flat upon the cross-slide plate 29; the circular sewing aperture 47 in the lower clamp-plates 24 being thus lowered over the needle-throat member 11 which engages the under surface of the work during the sewing. The stitch-forming mechanism is then started and the work-clamp is given its usual step-by-step feeding movements to place the stitches around the buttonhole.

When the sewing operation is completed and the stitch-forming mechanism comes to rest, the rapid-feed mechanism again comes into action to return the work-clamp to its initial position for the cutting of the button-hole and the sewing threads. Before the work-clamp is shifted away from sewing position, however, a second eccentric portion 94 of the cam 90 rocks the lever 88 to elevate the work-clamp to raise the lower clamp-plates clear of the needle-throat member 11, in which raised position the work-clamp is shifted to button-hole-cutting position, Fig. 5, and the sewing threads are drawn out from the needle-throat member, such threads extending at an upward inclination from the needle-throat member to the last stitch and being separated from the under surface of the work, whereby space is provided for the entry of the upper pointed blade 52 of the thread-cutter in its movement to thread-cutting position, as explained in my said co-pending application. Lastly, the button-hole-cutter levers 15, 16 are advanced and closed upon the work, as indicated in Fig. 5, and immediately opened and retracted, whereupon the work-clamps are automatically opened and the machine brought to rest.

Having thus set forth the nature of the invention, what I claim herein is:—

1. A buttonhole sewing machine having, in combination, stitch-forming mechanism including a needle and a needle-throat member, a work-clamp adapted to clamp the work entirely around the area to be stitched, a buttonhole cutter, means for relatively moving the stitch-forming mechanism and work-clamp laterally of the needle into and out of

sewing relation, and means for relatively moving the work-clamp and needle-throat member transversely of the plane of the work prior and subsequent to the sewing operation and while the stitch-forming mechanism and work-clamp are in sewing relation.

2. A buttonhole sewing machine having, in combination, stitch-forming mechanism including a needle and a needle-throat member, a work-clamp adapted to clamp the work entirely around the area to be stitched, a buttonhole cutter, means for relatively moving the stitch-forming mechanism and work-clamp laterally of the needle into and out of sewing relation, and means for relatively moving the work-clamp and needle-throat member transversely of the plane of the work prior and subsequent to the sewing operation and while the stitch-forming mechanism and work-clamp are in sewing relation, said last mentioned means retaining the work-clamp and needle-throat member so relatively moved while the stitch-forming mechanism and work-clamp are shifted out of sewing relation.

3. A buttonhole sewing machine having, in combination, stitch-forming mechanism, a work-clamp, clamp-closing means, feed-cams and connections for relatively moving the stitch-forming mechanism and work-clamp first into sewing relation, then to sew around a buttonhole and then out of sewing relation, and means running with said feed-cams for lifting the closed work-clamp before the stitch-forming mechanism and work-clamp are relatively moved out of sewing relation.

4. In a sewing machine, a needle, a needle-throat member, a work-clamp, clamp-closing means, a thread-cutter, means for lifting the closed work-clamp, means for shifting the closed and lifted work-clamp laterally of the needle to thread-cutting position spaced from stitching position, and means for operating the thread-cutter with the work-clamp in its lifted position.

5. A buttonhole sewing machine having, in combination, a bed, stitch-forming mechanism, a work-holder, means for relatively moving the stitch-forming mechanism and work-holder to sew around a buttonhole and for relatively moving them into and out of sewing relation, a shaft journaled crosswise of said bed, a thread-cutter, a cam on said shaft and connections for operating said thread-cutter, and a second cam on said shaft and connections for relatively moving the work-holder and needle-throat member vertically.

6. In a sewing machine, stitch-forming mechanism, a work-clamp, a thread-cutter mechanism mounted below the work-clamp, a cam-shaft, a thread-cutter operating cam, on said shaft and an additional cam on said shaft and connections for lifting the work-clamp for the operation of the thread-cutter.

7. In a sewing machine, stitch-forming mechanism, a needle-throat member, a work-clamp, means for relatively feeding the stitch-forming mechanism and work-clamp to sew a group of stitches and for relatively separating the stitch-forming mechanism and work-clamp transversely of the needle-path after the sewing is completed, a thread-cutter mounted below the work-clamp, and means operating independently of the thread-cutter for relatively separating the work-clamp and needle-throat member vertically for the operation of the thread-cutter.

8. In a buttonhole sewing machine, in combination, stitch-forming mechanism including a reciprocating needle, a needle-throat member, a buttonhole-cutter, a work-holder having a stitching aperture to receive the needle-throat member and also having means for clamping the work substantially entirely around such aperture, feeding mechanism for producing relative movement between the stitch-forming mechanism and work-holder to sew around a buttonhole and for relatively separating the stitch-forming mechanism and work-holder to permit the work-holder and buttonhole-cutter to assume cutting relation in a position spaced from the stitch-forming mechanism, and means for relatively moving the work-holder and needle-throat member vertically and for holding them so relatively moved for the operation of the buttonhole-cutter.

9. A buttonhole sewing machine having, in combination, stitch-forming mechanism including a needle, a work-clamp, a thread-cutter, means for shifting the work-clamp laterally of the needle from sewing position to thread-cutting position, clamp-lifting means mounted on and travelling with the work-clamp, and means for actuating the clamp-lifting means while the work-clamp is in sewing position, said means permitting the work-clamp to be shifted to thread-cutting position while held lifted by said actuating means.

10. A buttonhole sewing machine having, in combination, stitch-forming mechanism including a needle, a work-clamp, a thread-cutter, means for shifting the work-clamp laterally of the needle from sewing position to thread-cutting position, clamp-lifting means mounted on and travelling with the work-clamp, and means for actuating the clamp-lifting means while the work-clamp is in sewing position, there being a travelling connection between said last two mentioned means in a line parallel to the direction of travel of the work-clamp.

11. In a buttonhole sewing machine, in combination, stitch-forming mechanism, a work-clamp having a travelling movement to and away from the stitch-forming mechanism, clamp-closing means, and means for lifting the closed work-clamp before the lat-

ter is moved away from the stitch-forming mechanism.

12. In a buttonhole sewing machine, in combination, stitch-forming mechanism, a work-clamp having a travelling movement to and away from the stitch-forming mechanism, and means for lifting the work-clamp before the latter is moved away from the stitch-forming mechanism and maintaining it lifted until it is returned to the stitch-forming position.

13. In a buttonhole sewing machine, in combination, stitch-forming mechanism, a work-clamp, clamp-closing means, means for imparting a travelling movement to the work-clamp to carry the latter to and away from the stitch-forming mechanism, and means independent of said first-mentioned means for lifting the closed work-clamp and holding it lifted in its travelling movement.

14. A buttonhole sewing machine having, in combination, stitch-forming mechanism, a work-clamp, means for relatively moving them into and out of sewing relation and to sew around a buttonhole, a thread-cutter, a shaft making one rotation per buttonhole-producing cycle, a cam on said shaft and connections for lifting the work-clamp, and a second cam on said shaft and connections for operating the thread-cutter, the first mentioned cam being timed to lift the work-clamp immediately upon completion of the sewing operation.

In testimony whereof, I have signed my name to this specification.

EDWARD B. ALLEN.
